SELF-FEEDING LIQUID DISPENSING AND
DEODORIZING DEVICEMartin M. Reynolds, Old Greenwich, Conn., as-
signor to West Disinfecting Company, a corpo-
ration of New York

Application July 26, 1950, Serial No. 175,995

4 Claims. (Cl. 299—22)

1

The present invention, while useful in other applications has particular utility in wash rooms and serves to eliminate disagreeable odors arising from the bowls of sanitary equipment. It is of the type that dispenses a suitable liquid, preferably an oil, for deposit upon the surface of the liquid in the bowl of the sanitary equipment in order to prevent the escape of odors therefrom and the oil is preferably perfumed in order that any odor that may develop before the oil completely covers the surface of the liquid in the bowl, will be masked.

The tightness of a wick if used to control the delivery of oil, is somewhat critical for if too tightly packed, it may too greatly restrict the flow for full efficiency, and if packed too loosely, the flow of oil therefrom may be at a rate faster than required, with consequent need for frequent servicing. As manufacturing variations in the weaving of a wick and the natural variations in the fibres themselves prevent accurate control of the wick flow rate, the use of a wick is often undesirable.

Where the hydrostatic head of the oil feeding such wick decreases with consumption of oil, the rate of feed will progressively decrease and if correct for a given head will be excessive for a higher head and inadequate for a lower head.

It is accordingly among the objects of the invention to provide a liquid, dispensing device of the above type which is relatively simple in construction, having but few parts, none of which are delicate or likely to become deranged, which device is relatively simple to service and recharge without likelihood of spilling and which will dispense liquid therefrom at a constant and uniform rate substantially regardless of the quantity of liquid remaining in the device, and which device will spread the liquid over a relatively large area before discharge from the device with resultant effective exposure for evaporation of perfume that may be contained in such liquid, and which will collect and dispense such liquid in drops.

According to the invention, the receptacle containing the liquid is provided with a porous wall portion through which the liquid oozes to form a film on the outer surface. Means are provided to maintain substantially a constant level in said receptacle so that the liquid therein will ooze therefrom at a constant rate of flow and means are desirably provided to alter the level of the liquid in said receptacle so that the rate of flow therefrom may be adjusted.

In a specific embodiment of the invention herein illustratively shown, the liquid receptacle

2

is desirably cup-shaped, preferably having a porous upstanding side wall and an impervious bottom wall or floor. The receptacle is desirably fed from a container for liquid positioned thereabove and having the mouth of its substantially vertical outlet extending downward into said receptacle and encompassed by the porous side wall and spaced from the floor thereof, whereby the level of the liquid in the receptacle will rise only to the mouth of the outlet and be maintained at such level as long as sufficient liquid remains in the container. Desirably means are provided to adjust the distance between the mouth of said outlet and the floor of said receptacle so that the level of the liquid in the latter may be varied to adjust the rate of flow therefrom.

Means are desirably provided to collect the liquid as it flows in a film down the outer surface of the porous wall of said receptacle. To this end, the receptacle desirably has a substantially cylindrical base of impervious material which serves as a gutter down which may flow the film of liquid that oozes through the porous wall. The gutter desirably has a plurality of tongues struck out therefrom, each being substantially trough-shaped and tapering to a point at its end. Thus as the film of liquid flows down each tongue and converges at the pointed end thereof, it will collect and will fall off when the drop thus accumulated has reached sufficient size.

In the accompanying drawings in which are shown one or more of various possible embodiments of the several features of the invention,

Fig. 1 is a perspective view of the device,

Fig. 2 is a longitudinal sectional view of the device on a larger scale taken along line 2—2 of Fig. 1,

Fig. 3 is a transverse sectional view taken along line 3—3 of Fig. 2,

Fig. 4 is a view similar to Fig. 3 taken along line 4—4 of Fig. 2, and

Fig. 5 is an exploded perspective view of the device.

Referring to the drawings, the dispensing device desirably comprises a receptacle 6, preferably cup-shaped as shown and having a porous wall portion, which may be of bronze or ceramic material, through which a suitable liquid in the receptacle, preferably a light mineral oil, may slowly ooze to form a film on the outer surface of said wall portion.

The mineral oil desirably has a viscosity in the order of 5 to 15 centipoises so that it may readily pass through the porous wall portion and preferably is perfumed by the addition thereto of a

suitable essential oil such as oil of wintergreen, the proportion of the essential oil to the mineral oil being selected as desired.

Although either the floor 6' or the upstanding side wall 7 of the receptacle or both could be porous, in the embodiment herein shown only the side wall 7 is of porous material and the floor 6' is desirably of impervious material.

The receptacle desirably has a substantially cylindrical base 7' which defines a gutter down which may flow the liquid which oozes through the porous side wall 7 and means are desirably provided to collect such liquid, so that it may be dispensed in drops.

To this end, the base 7' desirably has a plurality of substantially V-shaped slits 8 therein, defining substantially triangular trough-shaped tongues 8', concave in transverse section on their outer faces, with the side edges of said tongues converging toward their pointed lower ends 9. Thus, the film of liquid flowing down along base 7' will collect at the pointed ends 9 and when the drop thus accumulated has reached sufficient size it will be released.

In order that the liquid will discharge through the porous side wall 7 at substantially a constant rate, means are provided to maintain a constant level of liquid in said receptacle 6.

To this end a container 9' illustratively cylindrical in shape, is provided, positioned directly over receptacle 6 having preferably an axial outlet tube 10 depending from the floor 11 thereof about aperture 11' in said floor, into said receptacle, and encompassed by said upstanding side wall 7 with the mouth 10' of outlet 10 extending below the upper rim of wall 7 and above floor 6'. Thus the liquid flowing into said receptacle through the outlet 10 of container 9' will only rise to the mouth 10' of said outlet 10 thereby insuring that the level of liquid in the receptacle 6 will remain constant as long as there is a sufficient supply of liquid in the container 9'.

In the embodiment herein shown, the container 9' has a conventional air tight removable snap type cap or closure 13 for its filling aperture or mouth 12 in the short neck 12' of the container.

Although the container 9' and the receptacle 6 could be mounted in any suitable manner, they are preferably positioned in a casing 13' which, as shown in Fig. 5, desirably comprises a substantially U-shaped shell 14 having side walls 14' and 15 and a top wall or cover 15', said shell 14 desirably being open at the bottom and rear thereof and having a plurality of vents 16 in the lower portion of the side walls 14' and 15.

Although the top wall 15' of the casing 13' could be formed integral with the shell 14, it desirably is a separate piece, preferably a substantially tray-shaped member which is rigidly affixed to the shell. To this end as shown in Figs. 1 and 2, a retaining strip 16' preferably substantially U-shaped as shown, is affixed on the inner surface of the shell as by welding, with its upper portion 18 protruding above the top rim 17 thereof.

The rim 19 of the substantially tray-shaped cover 15' is telescoped over the protruding portion 18 of the retaining strip 16' and is desirably affixed thereto as by welding. Preferably the dimensions of the rim 19 and the shell 14 are so related, that when assembled as above described, adjacent edges 21 and 22 of shell 14 and rim 19 will abut as shown.

The shell 14, as shown in Fig. 5, desirably has

inturned lateral flanges 23 on the open rear thereof, each of said flanges 23 desirably having an inwardly bent lip 24 along its length extending at right angle thereto.

Associated with the casing 13' is a back plate 25 and a wall plate 26, said plates desirably being secured together and having a bottom piece 27 rigid therewith and extending laterally outward from said plates. As shown in Figs. 2 and 5, a substantially U-shaped retaining strip 29 is affixed as by welding to the inner faces of the upstanding wall 28 of the tray-shaped bottom piece 27, with the upper portion 31 of said strip 29 protruding above the wall 28.

The floor 35 of the bottom piece 27, which is concave as shown, is downwardly inclined, desirably from the front to the rear thereof and has openings 36 therein, preferably formed in the tops of substantially hemispherical rising protuberances 37 which may be pressed out from said floor. Desirably a channel 38 is formed in said floor near the rear thereof leading into a discharge outlet 39, the latter having a nozzle 40 associated therewith.

As shown in Figs. 4 and 5, the back plate 25 is desirably channel shaped, having lateral flanges 41 and 42 which are reversely bent as at 43 to form retaining grooves for the lips 24 of the shell 14 positioned on the juxtaposed plates 25 and 26 in the manner hereinafter to be described.

The wall plate 26 is also preferably channel shaped and slightly longer than the back plate 25, said wall plate 26 desirably having obliquely extending lateral flanges 44 and 45 and having a bent portion at the lower end thereof defining a transverse lip 46. The lateral flanges 44 and 45 of the wall plate 26 are sufficiently spaced so that when the plates 25 and 26 are affixed together as by welding, the lateral flanges 44 and 45 of the wall plate 26 will straddle the lateral flanges 41 and 42 of the back plate 25.

A yoke 47 desirably serves to assemble the back plate 25, the wall plate 26 and the bottom piece 27. This yoke has a cross piece 48 with vertical slots 49 from the lower edge near each end thereof which slots straddle the rear wall 51 of the bottom piece 27. The legs 52 of yoke 47 lie against the inner faces respectively of the sides 53 of the retaining strip 29 to which they are securely affixed preferably by welding. Desirably the lower ends of the lateral flanges 41 and 42 of the back panel 25 straddle the cross piece 48 of the yoke 47, as shown in Figs. 2 and 5 with the transverse lip 46 of the wall plate 26 resting against the lower portion of said cross piece 48 and affixed thereto as by welding as at 55.

As shown in Fig. 2 the container 9' is desirably releasably mounted in the casing 13' so that it is vertically movable therein. To this end the back plate 25 has a longitudinally extending hook 81 desirably struck out therefrom on which the container 9' may be hung by means of the cross piece 83 of a substantially U-shaped bridge 82 which is affixed to the wall of the container.

The receptacle 6 is removably supported with the lower edge 89 of its base 7' resting on the floor of bottom piece 27 and encompassing the protruding bosses 37 thereon. The lower edge of said base desirably has a plurality of notches 91 therein to permit the liquid flowing down the gutter onto the floor of the bottom piece to pass through said notches so that it may escape from the nozzle 40.

Means are desirably provided to permit displacement of the mouth 10' of outlet 10 relative

to floor 6' of said receptacle 6 so that the level of the liquid in said receptacle may be varied. This could be effected by raising or lowering the receptacle 6, but in the preferred embodiment herein shown the outlet 10 is arranged to be raised or lowered. To this end an internally threaded sleeve 92 may be affixed at one end, as by welding, to depend from the undersurface of the bottom wall 11 of said container and a screw 93 is threaded into said sleeve with the free end 94 of said screw resting on the floor 6' of said receptacle. It is thus a relatively simple matter to raise or lower the mouth 10' of the outlet 10 with respect to the floor of the receptacle by merely turning the screw 93 in either a clockwise or counterclockwise direction before positioning the container in the casing 13'.

In order to prevent escape of liquid from the outlet 10 of the container 9', when the latter is filled through the filling mouth thereof, with possible overflow of the receptacle 6, suitable valve means are provided for the outlet 10' preferably constructed to close said outlet when the cap 13 is removed from the rim 12' of the mouth 12 for filling of said container, and to open said outlet 10 when the cap 13 is affixed on said rim 12'.

To this end an actuating rod 71 extends axially of said container, and is of such length that it may protrude above the rim 12' of mouth 12 and below the opening 11' in bottom wall 11. A valve closure member, desirably a substantially conical valve head 72 is affixed to the end of the actuating rod 71 which extends through opening 11', so that the conical portion 73 of the valve head 72 may coact with the mouth 10' of the outlet 10 to seal the latter.

Means are desirably provided to retain the valve head 72 in sealing position with respect to mouth 10' when the cap 13 is removed from the rim 12' and to move said valve head 72 away from the mouth 10' when cap 13 is positioned on rim 12'. To this end a coil spring 76 is desirably provided, encompassing the lower portion of the actuating rod 71, said spring being compressed between the bottom wall 11 and a disc or collar 77 affixed on said actuating rod 71. Thus the spring will tend to urge the collar 77, and hence the actuating rod 71 to its uppermost position. However as the movement of the actuating rod 71 is restrained by the cap 13, the valve head 72 will be spaced from the mouth 10' of the outlet 10. When the cap 13 is removed from the rim 12', the upper end 78 of the actuating rod 71 under the urging of coil spring 76 will protrude from the filling mouth 12, thereby causing the valve head 72 to seat on the mouth 10' of the outlet 10 to close the latter.

To install the device, the assembled back plate 25, wall plate 26 and bottom piece 27, are mounted on a wall as shown in Fig. 2 by means of screws 98 which pass through suitable openings 99 in the back plate and wall plate. The receptacle 6 is then positioned on the bottom piece 27 with the lower edge 89 of the base of the receptacle resting on said bottom piece and encompassing the openings 36 therein. The container 9' is then mounted on the back plate 25 by sliding the bridge 82 of such container over hook 81. With the cap 13 removed from the rim 12' of the filling mouth 12, the valve head 72 will be seated against the mouth 10' of the outlet 10 sealing the latter. After the container is filled with a suitable liquid, the cap 13 is pressed over rim 12' to seal the filling mouth 12 and to depress the actuating rod 71 thereby moving the valve head 72 away from the

mouth 10' of outlet 10 to open the latter. The liquid in the container will thereupon flow through the outlet 10 to fill the receptacle 6 to the level of the mouth 10' of said outlet 10, the liquid level being preferably set by adjusting the screw 93 in threaded sleeve 92 in the manner heretofore described.

The casing 13' is then mounted on the back plate 25 by positioning the lips 24 of the casing in the grooves formed by the reversely bent lateral flanges 41, 42 of said back plate and lowering said casing until the bottom edge 101 thereof abuts against the upper edge 32 of the bottom piece 27, the oblique lateral flanges 44, 45 of the wall plate 26 preventing rearward displacement of said casing 13' as shown in Fig. 4.

As the upstanding wall 7 of the receptacle 6 is porous, the liquid therein will ooze therethrough and form a film which will flow down the outer surface of wall 7 and also down the gutter 7'. The odor of perfume in such liquid will escape through the vents 16 in side walls 14' and 15 of the casing 13' and through holes 36. As the film of liquid flows down the gutter 7' it will gather at pointed ends 9 of the trough-shaped lip portions 8' thereby forming a drop at each of such ends, which when they have grown to sufficient size, will drop and splatter as they hit the floor of the bottom piece 27, to disperse the liquid for enhanced dispersion of the perfume therein through vents 16 and holes 36.

By reason of the inclined floor of the bottom piece 27 the liquid thereon will flow down said floor into the channel 38 at the rear thereof and then be discharged in drops through the nozzle 40. Because of the hemispherical protuberances 37 on the bottom piece the liquid flowing down the floor thereof will not escape through the openings 36 therein, which permit the perfume vapors to flow out of the casing and also provide for the flow of air into the casing to increase the dispersion of the perfumes in the liquid, through the vents 16.

With the construction above described, the level of liquid in the receptacle will remain substantially constant as long as sufficient liquid is in the container to fill such receptacle to the level of the mouth 10' of the outlet 10. As a result, the flow of liquid through the porous wall 7 of the receptacle 6 will remain substantially constant so that once the liquid level which determines the rate of flow, is set by adjusting the screw 93 to provide sufficient flow of liquid from the device to perform the desired function of masking and preventing disagreeable odors arising from the bowls of the sanitary equipment, the device will function properly with substantially no waste until substantially all the liquid in the container is exhausted.

Inasmuch as the rate of flow is substantially constant for any given setting of the screw 93, it is a relatively simple matter to determine the length of time it will take for the container to become exhausted. Hence the number of calls to service the device can be kept to a minimum.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I

75

claim as new and desire to secure by Letters Patent of the United States is:

1. An apparatus of the character described comprising a container for liquid having an outlet and a substantially cup-shaped liquid receptacle having an upstanding side wall of rigid material of substantially fixed porosity encompassing said outlet, and a floor of impervious material, said outlet being spaced from said floor, whereby liquid flowing into said receptacle will rise to the level of said outlet and will be slowly discharged at substantially uniform rate through said porous wall portion, said receptacle having a base of impervious material forming a gutter below said porous side wall, said gutter being aligned with the outer surface of said side wall, whereby the liquid discharged through said porous side wall will flow down said gutter, said gutter having means thereon to collect and dispense such liquid in drops.

2. The combination set forth in claim 1 in which said last named means comprises a plurality of substantially triangular trough shaped tongues on said gutter, each longitudinally concave on its outer face, the side edges of each tongue converging toward its lower end, said lower end extending outwardly from said gutter.

3. A liquid dispensing device comprising a casing, upright support means for said casing, a hook on said support means, a bottom piece for said casing, said bottom piece having a discharge outlet therein, a liquid receptacle positioned on the floor of said bottom piece, said receptacle having an upstanding wall portion of substantially fixed porosity, an upright container in said casing, said container having a substantially vertical outlet at the lower end thereof with its mouth positioned in said receptacle and spaced from the floor thereof, whereby the liquid in said container will flow into said receptacle and rise to the level of the mouth of said outlet and be slowly discharged at substantially uniform rate through said porous wall

portion to the floor of said bottom piece and through said discharge outlet, hook engaging means on said container engaging said hook on said support means so as to be movable vertically thereon and means to move said container vertically with respect to said upright support to vary the distance between the mouth of said outlet and the floor of said receptacle to adjust the level of the liquid in said receptacle.

4. As an article of manufacture a substantially cup-shaped liquid receptacle having an impervious floor and an upstanding rigid porous side wall, said receptacle having a base of impervious material forming a gutter aligned with the outer surface of said porous side wall, said gutter having a plurality of substantially triangular trough shaped tongues each concave in transverse section on its outer face with the side edges of each tongue converging toward its lower end, said ends extending outwardly from said gutter.
